CRAYON HOLDER

Filed Nov. 8, 1930

Inventor:
Sticolino Bafetti

UNITED STATES PATENT OFFICE

NICOLINO BAFETTI, OF CHICAGO, ILLINOIS

CRAYON HOLDER

Application filed November 8, 1930. Serial No. 494,272.

My present invention comprehends certain improvements in crayon holders, and the object of the invention is to provide a device of this character which is quite reliable and efficient in operation and which is particularly simple, durable and inexpensive in construction.

Another object of the invention is to provide a crayon holder with a crayon sharpening tool located at the writing end of the crayon holder for the purpose of reducing the size of the crayon to a smaller diameter at the writing point, thus affording the user a more pointed crayon when desired for marking various small articles to be labeled.

Another object is to provide a crayon holder with a sharpening tool at one end for reducing the crayon to a smaller marking point and a simple crayon clamping holder at the other end for a heavier marking effect.

Still another object is to provide a crayon holder for the crayon with clamping means in position for marking, and also means for sharpening by a conical shaped thimble sharpening tool secured loosely and revolvably on said clamping means.

The invention consists in the novel construction and combination of the several parts, as will be hereinafter fully set forth, and pointed out in the appended claim.

Reference is to be had to the accompanying drawing, forming part of this specification, in which similar characters of reference indicate corresponding parts in the various figures, in which—

Figure 1 is a longitudinal elevation of a preferred form of my crayon holder;

Fig. 2 is a longitudinal sectional view on line 2—2 of Fig. 1;

Fig. 3 is a detail view of the conical shaped thimble sharpening tool detached from the main tubular body of the crayon holder;

Fig. 4 is an elevational view of the tubular crayon holder and its associated parts;

Fig. 5 is a transverse sectional view taken on line 5—5 of Fig. 2;

Fig. 6 is a transverse sectional view taken on line 6—6 of Fig. 2;

Fig. 7 is a transverse sectional view showing very clearly the cutting edge of the coni-

cal shaped hollow thimble sharpening tool for the crayon;

Fig. 8 is a modification illustrating a double crayon holder, employing a crayon sharpening tool at one end and a crayon clamping means at the other end, showing some parts in section and elevation;

Fig. 9 is a longitudinal sectional view of still another modification, illustrating a crayon holder with a crayon sharpening tool detachably supported loosely for rotation on said clamping means.

The reference character A represents the tubular body or casing, which may be made of any suitable material, for example metal, celluloid, rubber or wood, and the said body A is open at both ends except for a removable cap piece G, and is provided with a longitudinal slot B of suitable length to accommodate a thumb screw C which in turn is threaded into a crayon cup follower D. The thumb screw C is for the purpose of feeding the crayon E and cup follower for writing position and for feeding and exerting pressure toward the conical-shaped sharpening tool F, when desired.

The one end of the tubular member is closed as by a threaded cap-piece G, more for ornamentation, although the cap-piece can be removed to replenish a new piece of crayon; but a more expeditious mode of refilling the crayon holder would be by withdrawing the conical-shaped sharpening tool F, which is only snapped on as will be clearly seen from the drawing. The tool F has an annular beaded groove f which is forced into engagement with two diametrically located lugs b—b of the tubular body B. Therefore it will be understood that the tool F can readily be withdrawn and replaced.

Now describing the conical-shaped sharpening tool F more fully, I provide a cutting or shaving blade f¹ within a slot f² through which the thin shavings removed from the crayon issue. The crayon E is supported in a frusto-conical shaped follower cup D at one end in the tubular body A, and has additional bearing supporting the conical-shaped sharpening tool F as indicated by the reference character x. Of course, this additional

support is only to be had after the progress of sharpening of the crayon is effected. Therefore, it will be apparent from the foregoing that by such a two-bearing support for the crayon at x and w , a more perfect sharpening reduction of the crayon is effected, thus preventing breakage of the crayon.

To afford a more easy withdrawal and replacement of the conical-shaped sharpening tool F, I provide several slits $a-a$ at the end of the tubular body A, which will yield during the disengagement and engagement of the groove f of the sharpening tool F and the lugs $b-b$ of the tubular body A.

In Figure 8 is illustrated a modified construction embodying the same mechanical expedients illustrated in Figures 1 to 7 inclusive, and adding a threaded crayon clamping thimble H to be received upon the threaded portion H^1 of the tubular body A. An extra cup follower D^1 is employed for the crayon E^1 for supporting the inner end of the crayon, but without employing a thumb-piece which is not required, as the one thumb-piece C will suffice to feed either crayon E and E^1 , respectively, for sharpening and writing.

The features of the threaded clamping thimble H and threaded portion H^1 of the tubular body A are the same as my co-pending application, filed December 12, 1929, Ser. No. 413,546, and therefore will not be further described.

The advantage gained in this construction is that, the user is capable of using either a heavy marking crayon or a lighter one, as the occasion may require.

The modification illustrated in Fig. 9 of the drawing, the crayon holder is constructed as in Fig. 8 as designated at M, but adding the conical-shaped sharpening tool F for the crayon, as above described, as in Figs. 1 to 7 inclusive. The clamping thimble tool H is provided with the lugs $b-b$ to receive the groove f of the conical-shaped sharpening tool F, as before described in the preferred form. The ends of the tubular body are slit as at h to yield for compression against the crayon.

The advantages gained in the construction of parts as illustrated in Fig. 9 are these: First the user can be afforded the use of a smaller diameter crayon and, if desirous of a larger one, the user will withdraw the sharpening tool F from the crayon holder, withdraw the crayon, reverse the ends and again insert the crayon, then clamping the crayon for use.

I am aware that many articles are on the market for holding and sharpening crayons and the like, but I am not aware of a combination of the mechanical expedients disclosed herein.

Having thus described my invention, what I claim as new, and desire to secure by Letters Patent, is:

A holder for marking crayons, comprising a tubular body having a slot made therein, a cup follower conically bored to receive a marking crayon, slidably mounted in the said tubular body, a thumb-piece passed through said slot of the body into the aforesaid cup follower, said tubular body having a threaded portion to receive a clamping thimble for the crayon, and lugs provided on said thimble for engaging and retaining a conical-shaped crayon sharpening tool mounted for rotation on said clamping thimble, substantially as set forth.

In testimony whereof I hereunto set my hand and seal this 6th day of November, 1930.

NICOLINO BAFETTI.
